(57) CLAIM

The ornamental design for a two-piece medical uniform set, as shown and described.

DESCRIPTION

FIG. 1 is a front perspective view of the upper portion of the two-piece medical uniform set showing my new design;

FIG. 2 is a front view thereof;

FIG. 3 is a rear view thereof;

FIG. 4 is a left view thereof;

FIG. 5 is a right view thereof;

FIG. 6 is a front perspective of the lower portion of the two-piece-medical uniform set showing my new design;

FIG. 7 is a front view thereof;

FIG. 8 is a rear view thereof;

FIG. 9 is a left view thereof; and,

FIG. 10 is a right view thereof.

The broken lines shown in the drawings illustrate portions of the two-piece medical uniform set and form no part of the claimed design.
